(57) **CLAIM**

The ornamental design for a lamp as shown and described.

DESCRIPTION

FIG. 1 is a front perspective view of a lamp showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a portion of the perspective view of FIG. 1 enlarged for magnification purposes;

FIG. 10 is another portion of the perspective view of FIG. 1 enlarged for magnification purposes;

FIG. 11 is a portion of the perspective view of FIG. 2 enlarged for magnification purposes; and,

FIG. 12 is another portion of the perspective view of FIG. 2 enlarged for magnification purposes.

The dash-dash broken lines depict portions of the lamp that form no part of the claimed design. The dash dot dash broken lines shown in FIGS. 1, 2 and 9-12 depict boundaries of the enlarged area.
